US00D621415S

(12) **United States Design Patent**
Umezawa

(10) **Patent No.:** US D621,415 S
(45) **Date of Patent:** ** Aug. 10, 2010

(54) **PORTION OF LIQUID CRYSTAL PANEL
WITH ICON IMAGE**

(75) Inventor: **Asaki Umezawa**, Tokyo (JP)

(73) Assignee: **Ricoh Company, Ltd.**, Tokyo (JP)

(**) Term: **14 Years**

(21) Appl. No.: **29/341,700**

(22) Filed: **Aug. 11, 2009**

(30) **Foreign Application Priority Data**

Feb. 11, 2009 (JP) 2009-002779

(51) **LOC (9) Cl.** 32-00

(52) **U.S. Cl.** D14/492

(58) **Field of Classification Search** D14/485-495;
D18/26, 31-33; D20/11-12, 23-25, 29-32,
D20/36-38; 715/700-867, 973-977

See application file for complete search history.
